H. G. BARRETT

METALLIC REINFORCING CORE FOR GOLF CLUB SHAFTS AND THE LIKE,
AND METHOD OF MAKING THE SAME

Filed July 17, 1925

Inventor
Harold G. Barrett
By *John J. [Signature]*

UNITED STATES PATENT OFFICE.

HAROLD G. BARRETT, OF WILMETTE, ILLINOIS, ASSIGNOR TO BARBARITE CORPORATION, OF CHICAGO, ILLINOIS, A CORPORATION OF ILLINOIS.

METALLIC REENFORCING CORE FOR GOLF-CLUB SHAFTS AND THE LIKE, AND
METHOD OF MAKING THE SAME.

Application filed July 17, 1925. Serial No. 44,225.

To all whom it may concern:

Be it known that I, HAROLD G. BARRETT, a citizen of the United States, residing at Wilmette, in the county of Cook and State 5 of Illinois, have invented certain new and useful Improvements in Metallic Reenforcing Cores for Golf-Club Shafts and the like, and Methods of Making the Same, of which the following is a specification.

10 This invention relates to improvements in shafts for golf clubs and the like, but more specifically the invention relates to an improved metallic core for re-enforcing wooden shafts of this character, thereby 15 enabling the use of low grade wood in the manufacture of the shaft.

A further object is to provide an improved re-enforced wooden shaft for golf clubs and the like which will combine all 20 of the attributes of metal and the usual wooden shafts, and at the same time eliminate the disadvantages of both.

To the attainment of these ends and the accomplishment of other new and useful 25 objects as will appear, the invention consists in the features of novelty in substantially the construction, combination and arrangement of the several parts hereinafter more fully described and claimed and shown in 30 the accompanying drawing illustrating this invention, and in which

Figure 1 is a side elevation of a golf club having a shaft constructed in accordance with the principles of this invention applied 35 thereto.

Figure 2 is a detail cross sectional view of two of the wooden members from which the shaft is constructed.

Figure 3 is a view similar to Figure 2, 40 showing the wooden members assembled.

Figure 4 is a view similar to Figure 3 showing the channel reamed out for the reception of the core.

Figure 5 is a perspective view of the 45 metallic core.

Figure 6 is a cross sectional view of the metallic core.

Figure 7 is a cross sectional view of the wooden members of the shaft with the

metallic re-enforcing core in position there- 50 in, and before the shaft is turned down.

Figure 8 is a sectional view on line 8—8, 55 Figure 1.

Figure 9 is a sectional view on line 9—9, 55 Figure 1.

Figure 10 is a cross sectional view of a modified form of core.

Figure 11 is a cross sectional view of the wooden shaft with the core as shown in 60 Figure 10 in position therein.

Figure 12 is a detail.

In carrying this invention into operation there are provided a plurality of pieces or strips 15 of any suitable material such as wood or the like, and each of the pieces is 65 provided with a longitudinal channel 16 opening through one face thereof. These members 15 are adapted to be placed together so that the channel in each registers with the channel in the other to form an 70 opening extending lengthwise of the shaft to be formed.

The members 15 are secured together in any suitable manner such as by means of 75 glue or cement.

After the parts have been assembled as shown in Figure 3 the opening formed by the channels 16 is reamed out from one end of the members 15 as at 17, to form a tapering 80 opening.

A metallic re-enforcing core designated generally by the reference numeral 18 is provided and is constructed of any suitable material preferably tempered metal, and of any suitable gage or thickness, having some 85 inherent resiliency.

The core 18 is split longitudinally as at 19 for the entire length of the core and the edges of the split portion are turned inwardly as at 20 to form inwardly projecting flanges, and the natural resiliency of the core 18 is such that the flanges 20 will, when the core is not inserted in the shaft, 90 separate the flanges 20.

The core 18 is preferably tapered and is 95 adapted to be inserted into the shaft or the members 15 from which the shaft is formed, by passing into one end of the channel 16,

and the core is driven into the channel during which time the core is gradually contracted until it is fully seated, at which time the adjacent faces of the flanges 20 will abut each other as shown in Figure 7.

The natural resiliency of the core 18 will hold the same firmly against the wall of the channel and the flanges 20 abutting each other will prevent the core from collapsing while being driven into the shaft.

After the core has been thus seated the members 15 are then shaped to form the shaft by turning down the member 15 to the desired diameter.

18 The core is preferably anchored adjacent its ends to the shaft 15 so that the shaft will have the desired torque and at the same time possess the desired resiliency and flexibility.

Any suitable means may be provided for 20 thus anchoring the core and shaft such as a fastening screw or bolt 21 which passes through the shaft and the core and preferably has a threaded extremity 22 which is threaded into a portion of the shaft.

25 A similar fastening device 23 may be provided adjacent the other end of the shaft for securing that end of the shaft and core together while the intermediate portion of the shaft and core between the fastening devices 21 and 23 are detached from each other so as to permit of a slight relative movement between the shaft and the core thereby rendering it possible to produce the necessary torque in the shaft without causing the shaft 30 to break and at the same time the shaft will possess the necessary stiffness and rigidity as well as tensile strength.

The flanges 20 may be of the same width throughout the length of the shaft or may 40 be of increasing width from one end of the shaft to the other so that in a tapering shaft the same amount of material in the core will be provided at one end of the shaft as there is at the other end.

45 In the form of the invention shown in Figures 10 and 11, the core is sectional in construction and comprises a plurality of longitudinal sections 24. The longitudinal edges of the sections 24 are deflected inwardly as at 25 to form flanges so that when the core sections 24 are assembled the flanges 25 will abut and when the core is forced into the shaft 26 the flanges 25 will prevent the core sections from collapsing.

55 These core sections may be secured by their extremities to the shaft 26 so that these core sections will have a slight movement one with respect to the other to produce the necessary torque in the shaft without causing the shaft to break and at the same time the necessary stiffness, rigidity and tensile strength will be obtained.

With this improved construction it will be manifest that the inherent resiliency of the 60 core 18 will tend to expand the same and

cause it to bind upon the wall of the opening in the shaft in which the core is located.

With this improved construction it will also be manifest that a shaft for golf clubs and the like may be produced from wood of 70 low grade and quality, and while the shaft is shown as being constructed of two sections it is obvious that any number of sections may be provided.

While the preferred forms of the invention have been herein shown and described it is to be understood that various changes may be made in the details of construction and in the combination and arrangement of the several parts, within the scope of the 80 claims, without departing from the spirit of this invention.

What is claimed as new is:—

1. A shaft for golf clubs and the like comprising a plurality of wooden strips secured 85 together, and a hollow longitudinally split metallic core contracted and surrounded by the said strips.

2. A shaft for golf clubs and the like comprising a plurality of wooden strips secured 90 together, and a hollow longitudinally split metallic core contracted and surrounded by the said strips, the edges of the split portion of the core abutting each other.

3. A shaft for golf clubs and the like comprising a plurality of wooden strips secured 95 together, a hollow longitudinally split metallic core contracted and surrounded by the said strips, and flanges along the edges of the split portion of the core, the said 100 flanges abutting each other when the core is contracted.

4. A shaft for golf clubs and the like comprising a plurality of wooden strips secured 105 together, a hollow longitudinally split metallic core contracted and surrounded by the said strips, the edges of the split portion of the core abutting, and means adjacent the ends of the core for securing the core and shaft together.

5. A shaft for golf clubs and the like comprising a plurality of wooden strips secured 110 together, and a longitudinally split hollow metallic core closely surrounded by the said strips, the adjacent edges of the 115 split portion of the core abutting.

6. A shaft for golf clubs and the like comprising a plurality of wooden strips secured 120 together, and a longitudinally split hollow metallic core closely surrounded by the said strips, the adjacent edges of the split portion of the core abutting and held in engagement by the said strips.

7. A shaft for golf clubs and the like comprising a plurality of wooden strips secured 125 together, a longitudinally split hollow metallic core closely surrounded and housed by the said strips, and laterally projecting flanges along the longitudinal edges of the split portion of the core, the proximate 130

flanges on adjacent edges of the core sections abutting.

8. A shaft for golf clubs and the like comprising a plurality of wooden strips secured together, a longitudinally split hollow metallic core closely surrounded and housed by the said strips, laterally projecting flanges along the longitudinal edges of the split portion of the core, the proximate flanges on adjacent edges of the core sections abutting, and means securing the ends of the core and the shaft together, the portions of the core and shaft intermediate the said securing means being free for slight relative 15 rotary movement.

9. A shaft for golf clubs and the like embodying a plurality of wooden strips secured together, and a split resilient metallic core contracted and surrounded by said 20 strips, the longitudinal edges of the core abutting, the inherent resiliency of the core tending normally to separate the said edges.

10. A shaft for golf clubs and the like embodying a plurality of wooden strips secured together, a split resilient hollow metallic core contracted and surrounded by said strips, and flanges along the edges of the split portion of the core, the inherent resiliency of the core tending to separate the 25 said flanges, the said strips surrounding and contracting the said core to cause the said flanges to abut.

11. A shaft for golf clubs and the like embodying a plurality of wooden strips secured together, a split resilient metallic core contracted and surrounded by said strips, the longitudinal edges of the core abutting, the inherent resiliency of the core tending normally to separate the said edges, and 30 means adjacent the ends only of the core for fastening the core and strips against relative rotary movement.

12. A shaft for golf clubs and the like embodying a plurality of wooden strips secured together, a split resilient hollow metallic core contracted and surrounded by said strips, flanges along the edges of the split portion 35 of the core, the inherent resiliency of the

core tending to separate the said flanges, the said strips surrounding and contracting the 50 said core to cause the said flange to abut, and means adjacent the ends only of the core for fastening the core and strips against relative rotary movement.

13. The method of constructing shafts for 55 golf clubs and the like which consists in providing a non-metallic hollow shaft, then forcing into the shaft a hollow longitudinally split metallic core to cause the edges of the core to abut, and then shaping the exterior of the shaft.

14. The method of constructing shafts for 60 golf clubs and the like which consists in providing a non-metallic hollow shaft, then forcing into the shaft a hollow longitudinally split resilient metallic core to contract the core and cause the longitudinal edges of the split portion of the core to abut, and then shaping the exterior of the shaft.

15. The method of constructing shafts for 70 golf clubs and the like which consists in providing a plurality of strips of wood, then longitudinally grooving the strips, then securing the strips together to form a hollow wood shaft, then forcing into the shaft from 75 the end thereof a hollow longitudinally split metallic core to cause the longitudinal edges of the split portion of the core to abut and remain in abutment, and then shaping the exterior of the shaft.

16. The method of constructing shafts for 80 golf clubs and the like which consists in providing a plurality of strips of wood, then longitudinally grooving the strips, then securing the strips together to form a 85 hollow wood shaft, then forcing into the shaft from the end thereof a hollow longitudinally split resilient metallic core to contract the core and cause the longitudinal edges of the split portion of the core to abut and remain in abutment, and then shaping the exterior of the shaft.

In testimony whereof I have signed my name to this specification, on this 10th day of July, A. D. 1925.

HAROLD G. BARRETT.
